COMBINED CLOCK AND PERPETUAL CALENDAR

Franklin M. Wills, Chicago, Ill., assignor to Burwood
Products Company, Chicago, Ill.

Filed Aug. 4, 1971, Ser. No. 169,169

Term of patent 14 years

Int. Cl. D10—01

U.S. Cl. D42—7 H

FIG. 1 is a front elevational view of one embodiment of a combined clock and perpetual calendar, showing my new design;

FIG. 2 is a side elevational view thereof;

FIG. 3 is a top plan view thereof;

FIG. 4 is a bottom plan view thereof;

FIG. 5 is a front elevational view of a second embodiment of a combined clock and perpetual calendar, showing my new design;

FIG. 6 is a side elevational view thereof;

FIG. 7 is a top plan view thereof; and

FIG. 8 is a bottom plan view thereof.

I claim:

The ornamental design for a combined clock and perpetual calendar, as shown.
